AIRPLANE TOY

Filed Sept. 17, 1928 2 Sheets-Sheet 2

UNITED STATES PATENT OFFICE

SAMUEL I. BERGER, OF NEWARK, NEW JERSEY

AIRPLANE TOY

Application filed September 17, 1928. Serial No. 306,460.

The toy of the present invention is of the type in which a miniature airplane, normally resting on the ground, is connected to one end of a normally inclined counter-weighted beam or lever rotatably fulcrumed intermediate its ends on the top of a stationary column. The airplane motor drives a toy propeller which moves the plane over the ground at such speed that the centrifugal force developed coupled with the lifting action of the propeller is sufficient to overcome gravity and cause the plane to rise and fly in a circular path, turning the lever about the column.

The invention more specifically represents an improvement over the airplane toy disclosed in the copending application of Louis Marx, Serial No. 156,554, filed December 23rd, 1926. In this application a toy airplane of the general character described above is operable to perform stunts such as nose-diving and looping the loop while in flight.

An object of this invention is to provide a toy of this character in which the realism of the simulated stunt-flying is materially enhanced, the toy plane, either in normal flight or during the course of looping the loop or performing some other unusual operation accurately simulating a corresponding maneuver of a full-sized airplane.

Another object is to provide a toy airplane in which no ratchet is associated with the spring driving motor and a simple, practical form of automatic clutch serves to couple the motor and propeller shafts of the toy. Such a clutch not only automatically uncouples these shafts during winding but permits the propeller to spin by its momentum after the spring motor has been fully unwound. Thus the landing of the airplane is rendered more realistic, since under ordinary conditions the propeller is still turning when the toy comes to rest, as opposed to prior devices in which the propeller stops when the motor spring was spent, and while the plane was still in the air.

Other and more general objects are to provide a toy of this character in which both

simplicity and ruggedness of construction are attained and in which the accurate assembly of the various movable units which make up the completed toy is facilitated and expedited.

With the above noted and other objects in view, the invention consists in certain novel features of construction and combinations and arrangements of parts which will be more fully hereinafter described and pointed out in the claims.

The invention may be more fully understood from the following description in connection with the accompanying drawings, wherein:

Fig. 1 is a perspective view showing the toy in flight and illustrating diagrammatically in dotted lines the erratic action as well as the unusual path of travel of the airplane.

Fig. 2 is an enlarged longitudinal sectional view through the airplane.

Fig. 3 is a transverse sectional view taken approximately on the line 3-3 of Fig. 2, this view showing the airplane at rest coupled to the beam or lever.

Fig. 4 is a view similar to Fig. 3 but showing the airplane in flight and in a position where it is about to loop the loop.

Fig. 5 is a sectional detail on the line 5-5 of Fig. 3.

Fig. 6 is a similar view on the line 6-6 of Fig. 3.

Fig. 7 is an enlarged partially broken bottom plan view of the airplane.

Fig. 8 is a view similar to Fig. 7 but showing only a fragment thereof, and indicating the position occupied by the counter shaft either when the motor is being wound or after the motor spring is spent, and

Fig. 9 is a transverse sectional view taken approximately on the line 9-9 of Fig. 2.

Referring to Fig. 1 in a general way the reference numeral 10 designates the central supporting column upon the top of which a lever or beam 11 is rotatably fulcrumed, this lever preferably being formed in two hinged sections 11a, 11b and carrying at its middle a depending fulcruming and swivelling pin 11c rotatably mounted in the top of the column 10.

Detachably connected to opposite ends handle 43 back and forth the propeller of the lever are the motor driven toy airplane 12 and the counterweighted toy aircraft 13, the latter preferably simulating a 5 dirigible and being slightly lighter than the former, which normally rests upon the ground and maintains the lever in a tilted position with the dirigible fully elevated.

The construction of the dirigible, the 10 beam and the supporting pin 11c may be substantially similar to those disclosed in the prior application above referred to, save that the angularly offset extremity 14 of the airplane supporting end of the beam is 15 of tubular formation and provided with a longitudinal slot 15 therein (Fig. 6).

The present invention is more especially concerned with the construction of the airplane and the means for attaching it to the 20 beam.

The airplane body 16 is of elongated hollow form, preferably open at the bottom. It mounts a wing member 17, a figure 18 in 25 simulation of an aviator and is equipped with the usual toy landing gear, 19, propeller 20, propeller shaft 21, stabilizers 22 and rudder 23.

Extending transversely of the interior of the body near the rear end thereof is a 30 bearing plate 24 and toward the forward end of the body of a pair of parallel frame plates 25 and 26 extend transversely of the body and are preferably connected by an integral bridging piece 27. The propeller 35 shaft 21 journaled in the front wall 28 of the body and in the frame plate 25 is axially aligned with the main shaft 29 of the spring motor, such motor shaft being journaled in the plates 26 and 24 and having a rearward extension 30 projecting beyond the tail of the plane and bent to provide a winding key 31.

Motor shaft 29 is encircled by the usual coiled torsional spring 32, the latter being 45 anchored at one end to the frame plate 24 and at its other end within a drum 33 fixed to the motor shaft 29.

The operative connections between the motor shaft and the propeller shaft 21 include 50 a speed multiplying gear train consisting of a gear 34 fixed to the drum 33 and meshing with a pinion 35 on a counter-shaft 36 journaled in the plates 25 and 26. The opposite end of this counter shaft carries 55 a gear 37 meshing with a pinion 38 on the propeller shaft.

The means for locking the propeller against movement as the motor spring is wound, includes a slide rod 39, the forward 60 end of which is looped back providing a pair of forward runs 40 slidable in the front wall 28 of the body. Rod 39 at its rear end is provided with an offset 41 working in a slot 42 in the body proper and carrying an 65 operating handle 43. Thus by shifting the

blocking end 40 of the slide rod 39 may be selectively projected or retracted.

A novel feature of the invention is the manner in which I permit free winding of the motor spring while the propeller is locked, without the use of ratchets, pawls or any similar mechanism which is likely to get out of order. The desired result is accomplished by utilizing the entire counter-shaft unit consisting of the shaft 36, gear 37 and pinion 35 as an automatic clutch and by forming the forward bearing for the counter-shaft, to wit, the bearing in the plate 25 in the form of a diagonal slot 44 (see Fig. 9).

By virtue of this arrangement, with the propeller locked, rotation of the motor shaft 29 in a direction to wind the spring 32, will serve to cant the counter-shaft from its normal longitudinal position of Fig. 7 to the inclined position of Fig. 8, in which the gear 37 is disengaged from the pinion 38. As soon as the winding key 31 is released, however, the action of the gear 34 on the pinion 35 will tend to restore the counter shaft to the position of Fig. 7 and to move the gear 37 into mesh with the pinion 38. With the parts in this position the propeller will automatically be turned, as soon as the propeller blocker 40 is withdrawn.

The unique automatic clutching arrangement afforded by the shaft unit and its special mounting in the plate 25 serves an additionally useful purpose in that it permits the propeller to continue to spin by its own momentum even after the spring 32 has been fully unwound and is transmitting no further power through the speed multiplying gear train. As soon as the motor shaft stops there will be no further torque transmitted through the pinion 35 in a direction to hold the counter-shaft unit in propeller shaft coupling position. Consequently the end of the counter shaft which carries the gear 37 will drop by gravity into the bottom of the slot 44, thereby disengaging gear 37 from pinion 38, so that the propeller shaft will now spin free without carrying the load of the gear train. In the event that the countershaft has a tendency to stick and does not fall by gravity it will be automatically kicked into the bottom of the slot by the continued rotation of the pinion 38 when the gear 34 stops turning.

Fixed laterally upon the body of the airplane is a generally box-like sheet metal member 45 providing a pair of parallel bearing plates 46 in which a laterally projecting shaft 47 has a slidable bearing. The outer end of this shaft fits within the sleeve 14 and a row of outstruck lugs 48 enter the slot 15, preventing rotations of the shaft in the sleeve while a diametrically opposite

lug 49 on the shaft 47 limits the insertion of the shaft into the sleeve. Shaft 47 at its opposite end carries a ring gear 50 adapted to mesh at certain times with gear teeth 51 formed on the drum 33.

With the airplane in its normal position of rest and with the shaft 47 inclining downwardly from the end of the sleeve 15 the airplane body and its associated casing 45 tends to slide outwardly on the shaft 47 and cause a lug 52 on the gear 50 to enter a suitable slot 53 in the frame plate 46 whereby the airplane is held against rotation on the shaft 47.

When, however, the airplane is in flight, as shown in Fig. 4, and has reached a height where the arm 47 inclines upwardly from the end of the sleeve, the airplane will slide inwardly on the shaft 47, disengaging the lug 52 from its notch 53 and causing the engagement of the gear 50 with the gear teeth 51. In this latter setting a planetary motion is had which causes the airplane to revolve about its own central transverse axis. In this planetary motion the gear 50 serves as the sun gear while the gear 51 serves as the planet and carries the entire airplane body with it in its travel around the sun gear.

The operation of the device is substantially as follows:

Having assembled the beam on the column and detachably engaged the counter-balancing dirigible 13 and the airplane 12 with the respective ends of the beam, the airplane motor is wound. Prior to such winding operation, slide rod 39 will be pushed forward to block rotation of the propeller and the counter-shaft 36 will act automatically in the manner above described to permit free winding of the motor spring without the transmission of power to the propeller shaft. After the motor is wound the slide rod 40 is retracted and the airplane starts to travel in a circular path, developing centrifugal force, which, assisted by the counter-balancing weight at the other end of the beam, quickly causes the plane to rise from the ground.

With the plane at rest on the ground and during the course of its upward travel the engagement of the tongue 52 and slot 53 prevent any rotation of the airplane about the shaft 47 and the plane is consequently maintained at a normal and realistic angle of flight. When the plane reaches a height where the shaft 47 inclines upward instead of downward, the plane will slide inwardly on this shaft as shown in Fig. 4, thereby disengaging tongue 52 from slot 53 and causing intermeshing of the gears 50, 51 which will result in rotation of the plane on its main transverse axis in a realistic simulation of an airplane looping the loop.

During this erratic maneuver the air-

plane loses sufficient momentum so that it again slightly descends to the position shown in Fig. 3 in which position lug 52 again becomes operative to hold the plane in a normal angle of flight until sufficient speed is again developed to cause a second stunt to be performed.

The provision of lug 52 is particularly important in that it obviates the possibility of the plane travelling in an orbital path either on its tail, on its nose or upside down and assures the proper angle of the plane during the periods when it is not looping the loop. The rise of the plane from the ground, its landing and its normal flying are of necessity carried out in a lifelike and realistic manner.

Under ordinary conditions the spring motor will have become fully unwound before the plane lands, due to the momentum and centrifugal force developed by the plane. The use of the automatic clutching mechanism, however, permits the propeller shaft to rotate for a considerable length of time on its own momentum after the motor has ceased to function and insures landing of the plane with the propeller still turning, as opposed to the unrealistic action of prior toys in which the propeller stops with the motor.

In the foregoing description I have attempted to avoid the recitation of obviously conventional details, such, for instance, as the manner of attaching the various parts of the sheet metal toy together by the usual slot and tongue connections and have furthermore avoided precise descriptions of the toy landing gear and similar mechanism which is subject to a great variety of structural changes.

It will thus be seen that there is herein described a device in which the several features of this invention are embodied, and which device in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is as follows:

1. A self-propelled air-craft toy, including a support, a beam rotatable and tiltable thereon, a toy aircraft on one end of the beam, means counter-balancing said beam, a motor operated propeller means for causing the aircraft to rise and fly in a circular path, gravitationally released means to rotate the

air-craft on its transverse axis when a pre-determined angularity of the beam is obtained and means preventing such rotation in other positions of the beam.

- 5 2. A self-propelled air-craft toy including a supporting column, a beam rotatably fulcrumed thereon, a toy airplane at one end of the beam, means counter-balancing said beam, motor-operated propeller means on the 10 air-craft to cause it to rise and fly in a circular path, means normally sustaining the air-craft at a realistic angle of flight and means operable at certain angularities of the beam to rotate the air-craft about its trans- 15 verse axis.
3. A self-propelled air-craft toy including a support, a counter-balanced beam rotatable thereon, an airplane detachably connected to one end of the beam, motor driven means to 20 propel the air plane in forward flight, casually operable planetary gear means engageable to rotate the plane on its transverse axis and means normally locking the plane against such rotation.
- 25 4. A self-propelled air-craft toy including a support, a counter-balanced beam rotatable thereon, an airplane detachably connected to one end of the beam, motor driven means to propel the airplane in forward flight, 30 casually operable planetary gear means to rotate the plane on its transverse axis, means normally locking the plane against such rotation, the planetary gear means including a sun-gear detachably fixed to the end of the 35 beam, the airplane having limited sliding movement on the end of the beam and the stop means including inter-engaging stop devices on the airplane and sun gear.
5. As a new element in a toy of the class 40 described, a toy airplane including a spring motor driven propeller, a laterally projecting shaft fixed to the airplane and having limited sliding movement relative thereto, a gear on the shaft adapted to intermesh with 45 a motor-driven gear of the airplane to cause rotation of the airplane on its transverse axis, and means normally operative to prevent such rotation.
6. As a new element in a toy of the class 50 described, a toy airplane including a spring motor driven propeller, a laterally projecting shaft fixed to the airplane and having limited sliding movement relative thereto, a sun gear on the shaft adapted to intermesh 55 with a movable planet gear of the motor to cause rotation of the airplane on its trans- 60 verse axis, and means normally operative to prevent such rotation, such means being gravitationally controlled by the angularity of the shaft.
7. A toy airplane of the character adapted 65 to be attached to one end of a counterbalanced rotatably fulcrumed beam and to loop the loop while flying in a circular path, said 70 airplane comprising a spring motor includ- 75

ing a gear to act as a planet while the plane is looping the loop, a laterally extending shaft adapted to be fixed to the beam end and longitudinally of which the airplane has limited sliding movement, a gear fixed to 70 this shaft and acting as a sun gear when the airplane is slid in one direction, and means to retain the airplane against rotary movement on the shaft when the planet and sun gears are out of mesh.

8. A toy airplane of the character adapted to be attached to one end of a counterbalanced rotatably fulcrumed beam and to loop the loop while flying in a circular path, said airplane comprising a spring motor includ- 80 ing a gear to act as a planet while the plane is looping the loop, a laterally extending shaft adapted to be fixed to the beam end and longitudinally of which the airplane has limited sliding movement, a gear fixed to 85 said laterally extending shaft and acting as a sun gear when the airplane is slid in one direction, and means to retain the airplane against rotary movement on the shaft when the planet and sun gears are out of mesh, 90 said means comprising rotation blocker devices fixed relative to the airplane and shaft and interengaged as the airplane is in one extreme position lengthwise of the shaft.

9. Means for attaching a stunt-performing 95 airplane toy to the end of a counterbalanced rotary beam, said means including a slotted sleeve at the beam end, a shaft projecting laterally from the airplane body, means on the shaft received in the slot to prevent rotation of the shaft in the sleeve and means on the shaft engaging the end of the sleeve to limit the insertion of the shaft thereinto.

Signed at Newark in the county of Essex and State of New Jersey this 14th day of 105 September A. D. 1928.

SAMUEL I. BERGER.
